[57] CLAIM
The ornamental design for a vehicular telephone set or
similar article, as shown and described.

[**] Term: 14 Years

DESCRIPTION

[21] Appl. No.: 900,287

FIG. 1 is a front elevation illustrating a vehicular tele-
phone set or similar article showing our new design;
FIG. 2 is a rear view thereof;
FIG. 3 is a top plan view thereof;
FIG. 4 is a bottom plan view thereof;
FIG. 5 is a side elevational view from the left thereof;
FIG. 6 is a side elevational view from the right thereof;
FIG. 7 is a front perspective view thereof;
FIG. 8 is a front perspective view thereof in which a
hand set is taken off;
FIG. 9 is a front perspective view of the set mounted on
a vehicle dash; and
FIG. 10 is a front perspective view thereof, with the
handset taken off.
The broken lines are shown for illustrative purposes
only.
